LLOYD V. LEWIS, OF EDGEWOOD PARK, PENNSYLVANIA, ASSIGNOR TO THE UNION SWITCH & SIGNAL COMPANY, OF SWISSVALE, PENNSYLVANIA, A CORPORATION OF PENNSYLVANIA.

BUFFING DEVICE.

1,070,970.

Specification of Letters Patent.

Patented Aug. 19, 1913.

Application filed January 11, 1912. Serial No. 670,552.

To all whom it may concern:

Be it known that I, LLOYD V. LEWIS, a citizen of the United States, residing at Edgewood Park, in the county of Allegheny and State of Pennsylvania, have invented certain new and useful Improvements in Buffing Devices, of which the following is a specification.

My invention relates to buffing devices for absorbing the momentum of moving parts. A buffing device embodying my invention is particularly adapted for absorbing the momentum of the moving parts in a relay of the "vane" type, although its use is not limited to this particular application.

I will describe one form of buffing device embodying my invention and then point out the novel features thereof in claims.

In the accompanying drawings, Figure 1 is a view showing in side elevation a relay having applied thereto one form of buffing device embodying my invention. Figs. 2 and 3 are views showing in side and end elevation respectively, and on a larger scale, the buffing device shown in Fig. 1.

Similar reference characters refer to similar parts in each of the several views.

One feature of a buffing device embodying my invention is the provision of a movable weight or buffing member which is constrained by guides to movement in an inclined path. This weight normally rests at the lowest point of the path due to the action of gravity, but when it is engaged by a moving body whose momentum is to be absorbed it is moved upwardly in this path. During this upward movement the momentum of the moving body is gradually absorbed both by the work done in raising the weight against gravity and by the friction between the weight and its guides.

Referring to the accompanying drawings, the buffing device as here shown comprises a U-shaped frame-work 10 mounted with its sides in vertical planes. In these upright sides are cut two slots 11, directly opposite to each other and inclined from the horizontal. As here shown these slots are slightly curved upwardly, but this specific shape of the slots although preferable, is not essential to my invention. These slots serve as guides for a shaft 12 which is mounted to move freely in the slots, and upon which is rigidly mounted a roller 12. This shaft and roller taken together consti-

tute a buffing member or weight, which normally rests at the lowest point of the slots due to the action of gravity, but which is moved upwardly when engaged by a moving body.

Referring now particularly to Fig. 1, the relay here shown comprises a vane 14 of aluminum or other suitable material pivotally mounted at 15. This vane moves between the pole-pieces of a soft iron core 16 upon which are mounted one or more energizing windings 17. The vane is biased by gravity or otherwise to its lowest position, indicated by dash lines, but when the winding 17 is properly energized by alternating current the vane is rotated upwardly to the position in which it is shown in full lines.

18 is an oscillating shaft which carries contact members 19 and 20; this shaft is connected with the vane by means of a crank 21 and a link 22 eccentrically pinned to the vane, the connections being so arranged that when the vane occupies the position indicated in full lines, the "front" contact 20 is closed as shown, and when the vane occupies the lowest position of its stroke the "back" contact 19 will be closed and front contact 20 open.

When the energizing current in winding 17 is cut off or sufficiently reduced, the vane 14 will rotate downwardly under the influence of gravity. As here shown, a buffing device embodying my invention is employed for arresting the rotation of the vane when it reaches the lowest point of its stroke. The position of the lower edge of the vane when it strikes the roller 13 is indicated in dash lines in the drawing. The momentum of the vane and of the moving parts moves the roller and shaft upwardly in the slots, the momentum being gradually absorbed by the work done in raising the weight and by the friction between the shaft and the lower edges of the slots. This friction is of a considerable amount owing to the fact that the weight is prevented from rotating, because of the difference between the radius of the roller against which the vane presses and the radius of the shaft which moves in the slots. If the buffing device is properly proportioned to the momentum of the moving parts, the movement of the vane will be completely arrested before the weight has reached the upper end of the slots, and the parts will then either rest in such posi-

tion or will move slowly backward until the weight reaches the lower end of the slots.

If the vane 14 has any tendency to sustain oscillations of gradually decreasing amplitude, this tendency will be counteracted by the buffering device embodying my invention, because this buffering device is incapable of sustaining oscillatory motion. The reason for this is that the buffering weight moves in the two different directions—that is, up and down,—at two different speeds, and the reason for this last fact is as follows: Since the roller 13 is larger in diameter than its shaft 12, when a driving force is applied in the direction shown by the arrow in the drawing, that is, in a radial direction, the roller and shaft are constrained to slide in the guides without rotation. The energy of the driving member (the vane) is, therefore, consumed partly in friction, the remainder being transformed into potential energy by raising the weight against gravity. On the return or downward movement, the roller and shaft will rotate, and not slide, because then the only force between the roller and the vane is that due to the force of gravity, there being no force due to the deceleration of the vane, hence the force between these two members is considerably less than it was on the upward stroke; and because the inclination of the guide slots 11 is such as not to exceed the angle of repose of the roller and shaft with reference to the line of gravity. Hence, the downward stroke is accomplished at a comparatively slow speed, and only a small portion of the potential energy stored up in the weight is returned to the vane, the greater portion being transformed into kinetic energy of rotation of the roller and into heat due to friction between the roller and the vane.

From the foregoing it will be seen that any tendency of the vane to oscillate will be immediately counteracted by the buffering device embodying my invention, and that there will, therefore, be no chattering of the contacts operated by the vane.

In the preferred embodiment of my invention, the slots 11 are curved gradually upward, the lower ends being only slightly inclined from the horizontal, as shown in the drawings. When constructed in this manner the inertia of rest of the weight is overcome by moving the weight in an almost horizontal direction, so that the friction between the shaft and the slots is a minimum during the early part of the movement, and so that during this part of the movement the weight is being raised very slowly against gravity. Then as the weight is moved farther along in the slots it begins to rise, so that the angle between the line of

movement and the horizontal plane constantly increases, hence the work to be done constantly increases. This work consists in raising the weight against gravity, and in overcoming the friction between the weight and the slots. The increase in work done in raising the weight against gravity as the above-mentioned angle increases is due to the fact that the vertical component of the movement of the weight for a given angular movement of the relay vane constantly increases; and the increase of work done in overcoming friction is due to the fact that as the above-mentioned angle increases, the line of force between the vane and the weight constantly becomes more nearly at right angles to the lower surface of the guiding slots. Hence, it will be seen that because of the curvature of the guiding slots, the force acting in opposition to the movement of the vane is at first very small, and constantly increases, so that the vane is brought to rest without shock.

By means of a buffering device embodying my invention, the momentum of the moving parts is absorbed without sudden shock. There is therefore no tendency for "chattering" of the contacts when the vane is brought to rest, and all danger of injury to the vane and moving parts connected therewith owing to sudden stoppage is avoided.

Although I have herein shown and described only one form of buffering device embodying my invention, it is understood that various changes and modifications may be made therein within the scope of the appended claims without departing from the spirit and scope of my invention.

Having thus described my invention, what I claim is:—

1. In combination, a movable body whose momentum is to be absorbed; and a buffering device comprising two upright walls, oppositely disposed and parallel inclined slots in said walls, a shaft adapted to move freely in said slots, and a roller mounted upon the shaft and located in the path of said body.

2. In combination, a movable body whose momentum is to be absorbed; and a buffering device comprising a weight adapted to be raised by said body, and means for constraining said weight to movement in a path curved upwardly from the horizontal whereby the resistance offered by the weight is at first small and increases as the weight is moved upwardly, so that the movement of the body is arrested without shock.

In testimony whereof I affix my signature in presence of two witnesses.

LLOYD V. LEWIS.
